United States Patent Office

Des. 196,590
Patented Oct. 15, 1963

196,590

PANEL OR SIMILAR ARTICLE

Melbourne F. Smith, Lenoir, N.C., assignor to Broyhill
Furniture Factories, Lenoir, N.C., a partnership

Filed Oct. 12, 1962, Ser. No. 72,095

Term of patent 14 years

(Cl. D33—1)

The FIGURE is a front elevational view of my new design for a panel or similar article.

The back of the panel or similar article is conventionally plain.

I claim:

The ornamental design for a panel or similar article, as shown and described.
